UNITED STATES PATENT OFFICE

2,378,690

INK FOUNTAIN

Albert Dager, Los Angeles, Calif.

Application January 24, 1944, Serial No. 519,434

3 Claims. (Cl. 101—366)

This invention relates to printer's ink fountains, and has for an object the provision of a fountain which may be mounted within a chase.

It is ordinary practice to provide a large ink fountain which is secured to a press adjacent the distributing disc. Often, in small commercial work, different colored printing inks are utilized, which requires that the regular fountain be removed, thoroughly washed, the inking rollers cleaned, and the distributing disc washed before a different colored ink is placed in the fountain. Such a job is laborious and requires considerable time—ordinarily up to one hour.

The present invention contemplates the use of a fountain which may be placed in the chase along with the form where its intended use is for light commercial work. A plurality of these fountains may be provided, holding different colored inks so that it becomes a simple matter to replace a fountain within a chase, the only work on the part of the printer being that of cleaning the inking rollers and the distributing disc when a different colored ink is used. The task of cleaning rollers and a distributing disc is relatively simple and does not require much time.

An object of the present invention is the provision of a supplementary ink fountain which may hold different bodied inks, and wherein the fountain may be adjusted to permit flow of the inks regardless of the body thereof, therefrom.

Other objects include an ink fountain which is simple in construction, and inexpensive in cost of manufacture.

With the above mentioned and other objects in view, the invention consists in the novel and useful provision, formation, construction, association and relative arrangement of parts, members and features, all as shown in a certain embodiment in the accompanying drawing, described generally, and more particularly pointed out in the claims.

In the drawing:

Figure 1 is a fragmentary side elevation, partly in section, of a portion of a printing press and chase incorporating the invention.

Figure 2 is a longitudinal sectional view of the improved ink fountain.

Figure 3 is a top plan view of the ink fountain.

Figure 4 is a sectional view on the line 4—4 of Figure 2, and,

Figure 5 is a plan view of a chase within which is locked the improved ink fountain, together with a form.

Referring to the figures, the improved ink fountain includes an ink reservoir 1, a plunger 2, and means 3 whereby the plunger may be progres-

sively moved within the reservoir. The reservoir in the present instance is made up of two side plates 4 and 5, an end or back plate 6 interposed between the side plates 4 and 5, and a front plate 7, which is adjustably movable between the side plates. The reservoir also includes top and bottom plates 8 and 9. The top and bottom plates, together with the back and side plates, are conveniently held in assemblage by means of screws, designated generally as 10. I have found it convenient to groove the side plates 4 and 5 at 11 and 12 for reception of tongues 13 and 14 formed on the back plate 6.

The front plate 7 is provided with tongues 15 and 16, which fit within grooves 17 and 18, in the side plates 4 and 5. The front plate is provided with a forked or bifurcated member 19, which overlies the top 8. The top 8 is formed with a central screw-threaded bore 20 adapted to receive an externally threaded annular nut 21. The bifurcated member 19 engages the nut in an annular groove 22. The threaded portion of the nut engages the threads 20 in top 8, whereby upon turning the nut, the front plate may be raised or lowered relative to the side plates and base 9. Such raising or lowering of the front plate provides an adjustable orifice 23 between the lowermost end of the front plate and the top surface of the base 9.

The plunger 2 is so shaped as to have a reasonably close fit between the walls of the reservoir, and attached to said plunger is a stem 24. This stem is passed through the central opening of the annular nut 21. The stem is provided on its surface with longitudinally extending teeth 25, thus forming a rack. Spacedly secured to the top 8 are a pair of upstanding arms 26 and 27. Rockably secured to each upstanding arm by means of pins 28 are bell cranks 29 and 30. The upper arms of said bell cranks are tied together by a cross bar 31. Interposed between and having bearing engagement with arms 32 and 33 of said bell cranks is rod 34. This rod carries a detent 35 adapted to have engagement with the rack 25 on stem 24. The detent is urged into such engagement with the rack through the medium of a coil spring 36 wrapped around the rod 34, with one end secured to the rod while the opposite end engages arm 32.

Centrally carried by cross bar 31 is means 37 constituting a button 38 provided with a stem 39 and a head 40. The cross bar is provided with a central threaded bore 41 for reception of an annular nut 42 through which nut is passed the

stem 39. Interposed between the annular nut and the button 38 is a coil spring 43.

The operation, uses and advantages of the invention just described are as follows:

Referring to Figure 5, a chase 44 has placed therein form 45 and the improved ink fountain. The ink fountain and form are held rigidly within the chase through the medium of furniture, designated generally as 46, the furniture, form, and fountain being locked in position through the medium of quoins 47. It will be noted that the fountain is so positioned and locked within the case that the button 38 may be readily engaged by the platen. Referring to Figure 1, the rolls 48 are shown overlying the distributing disc 49 and the chase is secured in the usual manner, that is, by a chase holder. This platen is shown at 50. When the platen 50 closes, the button 38 is depressed. Contact with the button 38 will move the button inwardly relative to cross bar 41, and may or may not rock the bell cranks 29 and 30. If, however, the bell cranks are rocked, detent 35 by its engagement with a tooth of the rack 25 will move the stem inwardly of the reservoir which, of necessity, would move the plunger 2 downwardly of the reservoir, that is, toward the base 9. The bell cranks are immediately restored to the position shown in Figure 2 after such a rocking motion through the medium of one or more leaf springs 51 fixedly carried by the upstanding arms 26 and 27 and engaging at their free ends the arms 32 and 33 of the bell cranks. This rocking movement of the bell cranks is restrained in one direction by one or more plates 52 secured to the arms 26 and 27.

We now assume that it is desired to supply ink to the distributing disc through the medium of the inking rolls. The reservoir is filled with the character of ink desired, whether it be light bodied or heavy bodied and regardless of color. To do this, the nut 31 may be screwed upwardly relative to the top 8 so as to provide a large opening between the end of the front plate 7 and base 9. The ink may then be poured or squeezed through a tube through said opening and into the reservoir. It is assumed, of course, that the plunger 2 has been elevated to a position adjacent the top 8 through the simple expediency of releasing the ratchet from engagement with the rack. After the required amount of ink has been placed within the reservoir, the nut 21 is turned so as to adjust the space existing between the front plate and the base 9; in other words, providing an adjustable orifice depending upon the body of the ink. If it is light-bodied, the orifice would be small, whereas for heavy inks, the orifice may be large.

The fountain with the ink within the reservoir is then placed within the case and locked in position, in the manner heretofore set forth. After the inking rollers have passed over the form, the platen 50 closes and the button 38 is contacted, and if nut 42 is so adjusted relative to the cross bar that the spring 43 is compressed, the striking of the button will rock the bell crank arms and move the stem 24 due to the ratchet and rack arrangement. Such movement will, of course, move the plunger 2 downwardly to impose a pressure upon the ink within the reservoir tending to force the ink through the orifice 23. This ink so forced through the orifice is picked up by the inking rollers and distributed on the front

plate 7 and likewise onto disc 49. Thus, the ink in the reservoir is gradually forced through the orifice as the plunger descends within the reservoir. If it is not desired to move the stem for every excursion of the inking rollers, the nut 42 can be adjusted so as to release some of the compression on spring 43, which will allow the button and its stem to move without, however, rocking the bell cranks. Such a condition might be required if the ink is light-bodied, as it would tend to flow through the orifice without undue pressure being applied thereto through the medium of the plunger.

After the required run has been made utilizing the particular form and the chase, it may be desired to use colors. This is readily accomplished by placing another fountain in a chase containing the required form and placing the chase in the press. The inking rolls and the distributing disc are cleaned and the press is again ready for operation.

The square interior of the reservoir is purely illustrative, as the reservoir, either external or internal, may be of different shapes and forms, the only requirement being that its external shape be such as to permit it to be readily locked within a chase.

I claim:

1. In a printer's ink fountain, a reservoir comprising a side wall, base and top members secured to said side wall, and a wall movable relative to the side wall and base to provide and adjustable orifice between the base and an end of said movable wall; means for adjustably moving said movable wall comprising a nut in threaded engagement with the top member and carrying said movable wall, a plunger within said reservoir, a stem for said plunger extending through said nut, and means whereby the plunger may be progressively moved in one direction within said reservoir.

2. A printer's ink fountain adapted for placement within a chase, the said chase in turn being placed in a press and in such position that the inking rolls of the press receive ink from the ink fountain during movement of said rolls over the ink fountain and any form within said chase; said ink fountain including a reservoir for ink, a plunger within said reservoir for exerting a pressure on said ink, a stem for said plunger, and means for progressively moving said stem to cause progressive movement of the plunger within the reservoir; said means including a bell crank rockably secured to the reservoir, a pawl carried by the bell crank, a rack on said stem engageable by said pawl, and a spring-tensioned button carried by the bell crank for engagement with the inking rolls to rock said bell crank.

3. In a printer's ink fountain, a reservoir, a plunger and its stem movable within said reservoir, said stem provided with a rack, a bell crank rockably secured to the reservoir, a pawl carried by the bell crank and engageable with the rack, a button provided with a stem loosely mounted with relation to the bell crank, a coil spring surrounding the stem, and means for adjustably compressing the spring against the button to regulate the degree of movement of said button necessary to rock said bell crank and produce movement of the plunger stem through the rack and pawl arrangement.

ALBERT DAGER.
